UNITED STATES PATENT OFFICE.

JAMES R. CUNNINGHAM, OF DECATUR, ILLINOIS.

RAIL.

1,307,852.

Specification of Letters Patent. Patented June 24, 1919.

Application filed December 26, 1917. Serial No. 208,780.

To all whom it may concern:

Be it known that I, JAMES R. CUNNINGHAM, a citizen of the United States, a resident of Decatur, in the county of Macon and 5 State of Illinois, have invented new and useful Improvements in Rails, of which the following is a specification.

My invention relates to improvements in rails, and particularly rails to be used for 10 railroads, street-railways, interurbans and the like.

The principal object of this invention is the provision of a rail having a continuous tread and having adequate provision made 15 for expansion and contraction, due to changes of temperature, so that the rail will be strong in construction, efficient in service and provide a continuous tread or bearing surface to obviate the jolting and other inconvenience arising from the use of the present 20 standard rail construction.

Another object of this invention is the provision of a rail formed in two parts which complement each other to form the complete 25 rail, the parts overlapping so that at the joint in one part the tread of the other part will be without a joint, and will make the bearing surface continuous, the bases of the rail being separated a suitable distance so as to 30 permit the expansion and contraction, due to climatic conditions, and the fish plates being attached by means of bolts passing through elongated holes or apertures, for the same purpose.

35 To the accomplishment of the foregoing and such other objects as may hereinafter appear, my invention consists in the combination, construction and arrangement of parts hereinafter described and then sought 40 to be defined in the appended claim, reference being had to the accompanying drawings forming a part hereof, and which shows merely for the purpose of illustrative disclosure, a preferred embodiment of my invention, it being understood that various 45 changes may be made in practice within the scope of the claim without digressing from my inventive idea.

In the drawings,

50 Figure 1 represents a plan view of a rail constructed according to my invention;

Fig. 2 is a side elevation of the same;

Fig. 3 is a horizontal section taken on line 3—3 of Fig. 4;

Fig. 4 is a vertical section taken through 55 the rail, fish-plate and tie-plate;

Fig. 5 is a side elevation of a detail.

Fig. 6 is a detail side elevation illustrating the use of the ordinary fish-plate.

Referring now to the drawings, the number 1 designates the ties which are located suitable or standard distances apart and on which may be placed the usual tie-plates or chairs 2, if desired. The rails rest on these tie-plates and are held in place by the spikes, 60 as is well understood.

65 The rails themselves comprise the complementary parts, which include the head ball 3, web 4 and base 5. The head ball is provided with the tread or bearing surface 6 70 and is of substantially the shape and size of the standard rail at present in use. Of course the size of the rail varies according to working conditions, just as at present. One side of the head ball 3 is cut away or 75 reduced at 7 so as to fit the corresponding portion of the complementary rail member, as shown. The base is also cut away at 8 so as to leave a space 9 therebetween, to permit the necessary expansion and contraction, due 80 to the various changes in climatic conditions and temperature. The two parts are laid in overlapping relation as clearly shown in Fig. 1; that is, at the joint of one part, the tread or bearing surface of the other part is continuous and vice versa, so that the rail always 85 provides a continuous bearing surface for the rolling stock.

At the joint, I utilize the fish-plates 10 which may be of any standard construction, 90 and which are preferably long enough to cover the joint in both parts of the rail, though it is obvious that I may utilize one or a pair of fish-plates at each joint, according to desire and operating conditions. 95 These fish-plates are held in place against the web of the rail by means of the usual nut and bolt construction 11, which passes through apertures or holes therein and also through the elongated holes or apertures 12 100 formed in the web of the rail. This, of course, is for the purpose of permitting any expansion and contraction.

Fig. 4 taken in connection with Figs. 3 and 5 shows very clearly my invention. It 105 is there observed that the ball of each section of rail has one perpendicular straight face which is off-set very slightly from the

correspondingly perpendicular straight face of its web and that the corresponding perpendicular straight face of the flanged base is in a plane between these two straight 5 faces of the ball and flange, respectively.

It is to be understood that the sides of the tread or head of the rail members are made to fit tightly against each other so that they will be positioned snugly and smoothly together, and make a smooth bearing surface and also that the overlapping of the joint of the mate rails, makes this bearing surface continuous. An additional purpose in utilizing the two rail members for forming the 10 complete rail is to provide a rail of maximum strength which will give extended service. Not only that, but in case one part of the rail breaks, the other part will be held in place and will prevent accident, due to derailment or other causes. Of course, in addition to the securing means at the joint, the rail members are bolted together as often as deemed necessary and advisable to hold them together. All of these bolt holes are 15 20 25 formed so as to permit the movement of the rail in expanding and contracting.

It is also to be noticed that the outer edges of the tie-chairs or plates 2 are turned upward as at 13 so that the edges of the

rail members fit therein. This will hold 30 the rail members together and prevent them from spreading apart.

It is seen, referring particularly to Fig. 6, that the fish-plates may be of usual construction, one being provided for each joint 35 instead of the longer ones shown in Figs. 1 and 2 of the drawings.

What I claim is:—

In a rail, a pair of sections each having head, web and base portions, the head portions having vertical abutting inner faces which project beyond the web portions, and the base portions having inner sides with free and permanent space between said inner sides, the inner side faces of the base portions 45 being disposed outwardly beyond the meeting line of the inner faces of the head portions, the webs having free and permanent space therebetween and throughout their inner faces, a chair on which the base portions seat, said chair extending across said free and permanent space between the inner sides of the base portions, bolts to secure the sections together, and means to hold the base portions in rigid position on the chair. 50 55

In witness whereof I have hereunto affixed my hand this 4th day of December, 1917.

JAMES R. CUNNINGHAM.
